UNITED STATES PATENT OFFICE

122,937

DESIGN FOR A GAME BOARD FOR PUBLIC AMUSEMENT PLACES

Kenneth R. Caldwell, Buffalo, N. Y.

Application May 25, 1940, Serial No. 92,611

Term of patent 7 years

To all whom it may concern:

Be it known that I, Kenneth R. Caldwell, a citizen of the United States, residing at Buffalo, in the county of Erie and State of New York, have invented a new, original, and ornamental Design for a Game Board for Public Amusement Places, of which the following is a specification, reference being had to the accompanying drawing, forming a part thereof.

Figure 1 is a front view of the game board embodying my new design. Figure 2 is an end view thereof. Figure 3 is a top plan view of the same.

I claim:

The ornamental design for a game board for public amusement places, substantially as shown.

KENNETH R. CALDWELL.
